UNITED STATES PATENT OFFICE

2,630,314

FISHERMAN'S KNIFE

William M. Cadwallader, Pittsburgh, Pa.

Application December 26, 1951, Serial No. 263,199

3 Claims. (Cl. 265—63)

1

The present invention relates generally to new and useful improvements in fishermen's tools, and has for its primary object to provide, in a manner as hereinafter set forth, a device of this character comprising a novel combination of a knife, fish scaler, gaff hook and weighing scale.

Another very important object of the invention is to provide a compound tool of the aforementioned character comprising novel means for locking the weighing scale against operation in the handle when it is desired to use the knife blade.

Other objects of the invention are to provide a fisherman's knife of the character described which will be comparatively simple in construction, strong, durable, highly efficient and reliable in use, compact, light in weight, and which may be manufactured at low cost.

All of the foregoing and still further objects and advantages of the invention will become apparent from a study of the following specification, taken in connection with the accompanying drawing, wherein like characters of reference designate corresponding parts throughout the several views, and wherein:

Figure 1 is a view in longitudinal section through a knife constructed in accordance with the present invention.

Figure 2 is a view in side elevation of the device, showing the tool in use as a weighing scale.

Figure 3 is an end elevational view, looking at the device from the line 3—3 of Figure 1.

Figure 4 is a sectional view, taken substantially on the line 4—4 of Figure 1.

Figure 5 is an elevational view, looking at the handle end of the device.

Figure 6 is a detail view in end elevation of the blade shank.

Referring now to the drawing in detail, it will be seen that the embodiment of the invention which has been illustrated comprises a tubular handle 8 of suitable material. Secured by a pin 9 in one end portion of the handle 8 is a bushing 10, the outer end portion of which is internally threaded, as at 11.

The upper end portion of the handle 8 is counterbored, as at 12, and secured by a pin 13 therein is an internally threaded socket 14. An opening 15 in the socket 14, the purpose of which will be presently set forth, communicates with the socket bore.

Removably mounted on the handle 8 is a blade 16. The blade 16 includes a knife or smooth cutting edge 17, a toothed scaling edge

2

18, and terminates at its free end in a gaff hook 19.

The blade 16 is fixed on one end portion of a shaft or shank 20 which is mounted longitudinally in the bore 21 of the tubular handle 8 in spaced relation to the walls of said bore. Immediately adjacent the blade 16, the shank 20 is provided with a threaded portion 22 which screws into the portion 11 of the bushing 10.

10 The shank 20 further includes a threaded free end portion 23 which screws into the socket 14. It will thus be seen that the shank 20 is removably mounted in the bushing 10 and the socket 14. Immediately adjacent the threaded

15 end portion 23, the shank 20 has formed thereon a head 24 engageable in a seat 25 provided therefor in the socket 14. The head 24 and the thread 23 are notched, as at 26, to receive a locking pin 27 which is mounted on the free end portion

20 of a spring 28. The spring 28, in turn, is secured at one end on the lower end of the handle 8, as at 29. The opening 15 in the socket 14 accommodates the locking pin 27.

25 The coil spring 30 encircles the shank 20 in the bore 21 of the tubular handle 8. The ends of the coil spring 30 are engaged with the bushing 10 and the head 24. Communicating with the bore 21 is a longitudinal sight opening 31 in the handle 8 through which the shank 20 may be observed. Adjacent the longitudinal sides of the slot 31, the handle 8 is graduated, as at 32.

30 It is thought that the manner in which the device is used will be readily apparent from a consideration of the foregoing. Briefly, the smooth knife edge 17 is used for cutting, the toothed edge 18 of the blade 16 is used for scaling fish and the hook 19 is used as a gaff. For weighing a fish or other object, the device is held vertically with the handle 8 uppermost, as seen in Figure 2 of the drawing. The spring

35 28 is flexed to disengage the pin 27 from the notches 26 for permitting the shank 20 to be unscrewed from the socket 14 and the bushing 10. When thus unscrewed, the shank 20 is free to slide downwardly in the handle 8 against the tension of the coil spring 30. The fish or other object to be weighed is then suspended in any suitable manner, as at 33, from the hook 19 and the spring 30 is compressed under the load.

40 45 50 The head 24 on the shank 20 may then be observed through the slot 31 and read against the graduations 32 for ascertaining the correct weight of the fish or other object.

55 It is believed that many advantages of a fisherman's knife constructed in accordance with the

present invention will be readily understood and although a preferred embodiment of the device is as illustrated and described, it is to be understood that changes in the details of construction may be resorted to which will fall within the scope of the invention as claimed.

Having described the invention, what is claimed as new is:

1. A fisherman's tool of the character described comprising an elongated handle having a longitudinal bore therethrough, a bushing and a socket in the bore, said handle further having a longitudinal slot therein communicating with the bore, a slideable shank in the handle threadedly mounted in the bushing and the socket for securing said shank against sliding movement, and a blade on one end of the shank.

2. A fisherman's tool comprising an elongated handle having a longitudinal bore therethrough, a bushing in one end portion of the bore, a socket in the other end portion of said bore, a shank slideable in the bushing and engageable in the socket, coacting threads on the shank and in the bushing and the socket for releasably securing said shank against sliding movement, a coil spring in the handle encircling the shank and operatively connected thereto for yieldingly resisting sliding movement thereof in one direction, a blade on one end of the shank, and means for securing the shank against rotation in the bushing and the socket.

3. A fisherman's tool comprising an elongated handle having a longitudinal bore therethrough, a bushing in one end portion of the bore, a socket in the other end portion of said bore, a shank slideable in the bushing and engageable in the socket, coacting threads on the shank and in the bushing and the socket for releasably securing said shank against sliding movement, a coil spring in the handle encircling the shank and operatively connected thereto for yieldingly resisting sliding movement thereof in one direction, a blade on one end of the shank, and means for securing the shank against rotation in the bushing and the socket, said socket having an opening therein, said means including a head on the shank having a notch therein, a spring mounted on the handle, and a pin on said spring operable in the opening and engageable in the notch for securing the shank against rotation.
